UNITED STATES PATENT OFFICE

GEORGE W. CUMING, OF NEW YORK, N. Y., ASSIGNOR TO M. A. CUMING & CO. INC., A CORPORATION OF NEW YORK

MACHINE FOR TREATING HAT BODIES

Application filed January 11, 1928. Serial No. 245,856.

My invention relates to machines for treating hat bodies; that is, to machines for stretching the brims of unfinished hats, usually made of felt or the like.

More particularly stated, my invention comprehends an improved machine in which a hat body is placed, in order to stretch, flatten out and otherwise form into shape the brim, and then to shape the crown.

My invention also contemplates a machine of the general type just mentioned, but in which the hat body is subjected to the action of steam, so directed as to render the action of the steam as nearly as practicable uniformly distributed.

My invention also comprehends the use, in a machine of this general type, of a number of interchangeable forming members and parts associated therewith, for adapting the machine for use upon hats of different sizes.

In addition, my invention contemplates means for stretching the hat brim unequally in different directions, for reasons hereinafter stated in detail.

My invention further contemplates various improvements, parts and combinations of mechanism used for treating hat bodies.

Reference is made to the accompanying drawings forming a part of this specification, and in which like reference characters indicate like parts throughout the several figures.

Figure 1 is a substantially central cross section showing one form of my invention, certain movable parts being in the positions they occupy while the machine is stretching a hat brim.

Figure 1a is a section on the line 1a-1a of Figure 1, looking in the direction indicated by the arrows.

Figure 2 is a section on the line 2-2 of Figure 1, looking in the direction indicated by the arrows.

Figure 3 is a section on the line 3-3 of Figure 1, looking in the direction indicated by the arrows.

Figure 4 is a section corresponding to the middle portion of Figure 1, but showing certain movable parts as occupying different positions from the ones they occupy in said Figure 1.

Figure 5 is an enlarged fragmentary section of certain mechanism appearing in the left hand portion of Figure 1.

Figure 6 is a section on the line 6-6, of Figure 5, looking in the direction indicated by the arrows.

Figure 7 is a section on the line 7-7 of Figure 5, looking in the direction indicated by the arrows.

Figure 8 is a fragmentary plan view of the treadle shown at the lower portion of Figure 1.

Figure 9 is a fragmentary section taken upon the line 9-9 of Figure 1, looking in the direction indicated by the arrows.

Figure 10 is a front view, partly an elevation and partly a section, showing another form of my invention.

Figure 11 is a fragmentary side elevation of mechanism shown in the upper portion of Figure 10.

Figure 12 is a section on the line 12-12 of Figure 10, looking in the direction indicated by the arrows.

Figure 13 is a fragmentary plan of certain parts appearing in the upper portion of Figure 10.

Figure 14 is a fragmentary section, showing a form of mechanism for maintaining the shape of the hat crown while the brim is being stretched, but differing from the form shown in the middle of Figure 1.

Figure 15 is a detail of certain cam mechanism used for stretching the hat brim.

Figure 16 is a plan view of an elliptical member forming a part of the hat forming ring; said elliptical member being removable, and interchangeable with others of its kind, to accommodate hats of different sizes.

Figure 17 is a section through said elliptical member and an adjacent portion of the hat forming ring; the section being taken on the line 17-17 of Figure 16.

I will first describe the form of my device appearing in Figures 1 to 9 inclusive.

Mounted upon the upper portion of the framework are a pair of hangers 15, shown more particularly in Figure 9. Journalized in these hangers is a rocking shaft 16, and connected with this rocking shaft is a hand

lever 17, shown more particularly in Figure 9. A counterweight 18, shown in the figure last mentioned, is used for balancing the hand lever.

5 Mounted rigidly upon and carried by the rocking shaft 16 is a sector 19. The parts are so arranged that whenever the hand lever 17 is rocked by hand, the sector 19 and the counterweight 15 are correspondingly shifted in position. The hangers 15 are secured by aid of nuts 20.

10 Slidably supported by the framework are a pair of guide bars 21, 21, and extending between the tops of these guide bars is a cross piece 22, shown more particularly in Figure 1.

15 Carried upon the lower end of the guide bars 21, 21 is a lifting spider 23, of a form which may be understood by reference to Figure 2. The guide bars 21, 21 are at their lower ends provided with bolt heads 24, upon which the lifting spider rests.

20 Carried by the sector 19 and partially wound thereupon is a flexible supporting member 28, such as a chain. The upper end of this flexible supporting member is connected with the upper portion of the sector 19, as indicated in Figure 9. This flexible supporting member is secured at its lower 25 end to an adjusting bolt 29, somewhat in the nature of a turnbuckle. The adjusting bolt 29 carries an enlarged angular portion 30, whereby it may be turned and thus adjusted.

25 Another flexible supporting member 35 is also carried by and partially wound upon the sector 19. One end of this flexible member is connected with the lower portion of the sector, as indicated in Figure 9, the other end of this flexible supporting member being 40 secured to the cross piece 22.

30 The lifting spider 23 carries a presser foot 31, and encircling this presser foot is a collar 32. This collar is provided with slots 33, and extending through these slots are 45 clamping bolts 34, carried by the presser foot 31. The collar 32 is adjustable upon the presser foot. To adjust it, the bolts are loosened, the collar is moved, and the bolts are then tightened.

50 The purpose of the presser foot 31 with its collar 32 is to force a forming block into the hat crown, to a predetermined distance, in order to allow for shrinkage of the hat crown, as hereinafter more fully described.

55 The purpose of the guide bars 21, 21 is to guide the lifting spider 23 and parts carried thereby, as they are raised and lowered under control of the hand lever 17 and flexible supporting members 28 and 28a.

60 Each time the hand lever 17 is raised the sector 19 is rocked in a clockwise direction according to Figure 9, so that the guide bars 21, 21 are raised by means of the flexible supporting member 28; and each time the hand 65 lever 17 is brought down, the guide bars are

lowered by the pull of the flexible supporting member 28a upon the cross piece 22.

A steam chamber shown at 36, supported upon the cross beams 12, is used for supplying steam to the hat body, as hereinafter more particularly set forth.

70 Located within the bottom of the steam chamber is a baffle plate 36a, resting upon adjusting bolts 36b which serve as supporting feet, and which extend through slots 36c with which the baffle plate is provided. By adjusting the adjusting bolts 36b the spacing of the baffle plate from the bottom of the steam chamber, and the inclination of the baffle plate, may be controlled within certain limits.

75 Connected with the bottom of the steam chamber 36, at a point below the baffle plate 36a, is a steam pipe 36d, provided with a handle 37, and used for admitting steam into the steam chamber 36. The steam thus admitted, upon reaching the baffle plate 36a, is diffused and spread out, and its heat and its moisture are thus in great measure equalized throughout the steam chamber. The steam passes upwardly, and around the edges of the baffle plate, as may be understood from Figure 3.

80 Connected with the steam chamber 36 is an exhaust pipe 38, and connected with this exhaust pipe is a valve 39 provided with a handle 40 and having the form of a gate valve, as shown in Figure 1a. The exhaust pipe 38 leads to a blower, not shown, but indicated by the legend To Blower.

85 A baffle plate 38a is mounted within the steam chamber 36, so as to cover the adjacent end of the exhaust pipe 38. The purpose of this baffle plate is to equalize and distribute, as far as practicable, the partial vacuum created by the blower. By virtue of this arrangement, the baffle plates 36a and 38a cooperate with the each other to render the action of the steam as nearly as possible uniform upon different portions of the hat brim.

90 The direction of travel of the steam, in first passing into the steam chamber under control of the hand valve 37, and then passing out of the steam chamber and through the exhaust pipe, under control of the valve 39, is indicated by arrows and appropriate legends in Figure 1.

95 The steam chamber 36 is provided at its top with an annular flange 41, and resting upon this annular flange is a large ring 43, provided with an outwardly extending thin peripheral portion 44.

100 Resting loosely upon the large ring 43, which is stationary, is a cam ring 45, which is movable and has the form indicated for it in Figures 2 and 15. This cam ring is circular internally, and is provided upon its periphery with a number of separate cam surfaces 47, 47b. There are four of the cam surfaces 47, and four of the cam surfaces 47b. The cam surfaces 47b are considerably steeper 105

70

75

80

85

90

95

100

105

110

115

120

125

130

than the cam surfaces 47. The cam ring 45 is further provided with a handle 46. The operator by grasping the handle 46 can turn the cam ring to a limited extent back and forth.

5 Bolts 47a extend through the thin portion of the large ring 43, and also through the gasket 42 and the annular flange 36, as may be understood from Figure 7, so as to hold these parts securely together.

10 A hat forming ring is shown at 49, and is provided with a removable portion 48 of annular form. This hat forming ring is provided with a number of slots 50, extending radially outward, as may be understood from

15 Figure 2.

Extending loosely through the several slots 50 are pins 51, each carrying a roller 52, these rollers extending into engagement with the cam surfaces 47, 47b.

20 Each time the operator grasps the handle 46 and presses it toward the left, so as to turn the cam ring 43 in a clockwise direction according to Figure 15, all of the rollers 51 are moved radially outward. However, owing

25 to the steepness and great depth of the cam surfaces 47b as compared with the cam surfaces 47, the particular rollers in engagement with the cam surfaces 47b are moved further than the rollers in engagement with

30 the cam surfaces 47.

The purpose of this arrangement is to stretch the hat brim a little more in one direction than in another.

35 In most hats the brims are not circular, but somewhat elliptical. With the brim elliptical, it should be stretched in the direction of its longer axis to a greater extent than in the direction of its shorter axis.

40 Each pin 51 is carried by a foot plate 53, there being as many of these foot plates as there are rollers 52 and cam grooves 47. Each foot plate 53 is provided with a massive portion 54, having the proximate form of a crescent, as indicated in Figure 6, in order to afford a wide bearing surface suitable for gripping the hat brim, as hereinafter more particularly described.

45 Mounted rigidly upon the forming ring 49 are a number of guide rails 55, arranged in pairs as shown in Figure 7, the rails of each pair extending radially outward and parallel to each other, and held in position by bolts 56. Each foot plate 53, above described, is slidably fitted in between a pair of the guide rails 55, and within reasonable limits is movable back and forth; that is, adapted to slide radially inward and outward.

50 Each foot plate 53 is provided with a pair 60 of annular bearings 57, extending upwardly from it as indicated in Figures 5 to 7 inclusive. Extending through these bearings is a shaft 58, and journaled upon this shaft is a hub 59, carrying a pair of bearings 60, through which the shaft 58 extends. The

hub 59 carries a sector 61 which rocks with it upon the shaft 58, the sector being provided with a groove 62, of arcuate form. There are as many sectors 61 as there are rollers 52.

55 Each sector 61 is provided with a gripping surface 61a having the form of a crescent, and thus mating the adjacent gripping surface 54.

60 Each sector 61 carries a chain 63, partially wound within the groove 62, the end of the chain being secured to the sector at a point adjacent one end of the groove, as indicated in Figure 5.

65 Connected with each sector 61 are a pair of tensile springs 64, shown more particularly in Figure 6, these springs being also connected with the pair of guide rails 55 immediately adjacent. The purpose of the springs 64 is to maintain the rollers 52 pressed against the adjacent cam surface of 70 the cam ring.

75 A hat crown is shown at 65 and a hat brim at 66, these two parts being integral with each other and together comprising a hat body, as may be understood from Figure 4.

80 A crown block is shown at 66a, and is of proper form and size to fit into a hat crown 65, in order to form the crown and hold it in proper shape.

85 In order to rock the sectors 61 by means of the chains 63, I provide a treadle 67, shown more particularly in Figure 8. This treadle is journaled to rock upon a stationary shaft 68, and carries a spider 69, connected with all of the chains 63, as indicated more particularly in Figure 8.

90 Connected with each foot plate 53 and the sector 61 carried thereby is a coiled spring 61b. The purpose of this spring is to retract the sector into its normal position.

95 The treadle 67 is normally stationary and occupies a position at the upper limit of its travel, as indicated in Figure 1.

100 With the treadle in this position the sectors 61 each occupy the positions indicated for them in Figure 1. When the treadle is depressed, by the foot of the operator, the sectors 61 are thereby rocked into the positions indicated for them in Figure 4. Thus they first grip and then release the brim 66 110 of the hat, this gripping and releasing of the brim being entirely under control of the treadle, and being independent of the positions occupied from time to time by the foot plates 53, the latter being slid radially inward and outward, under control of the cam ring 45, which is operated by hand as above described.

115 Each time the cam ring 45 is rocked in a counter-clockwise direction according to Figure 2 by means of the handle 46 shown in that figure, the foot plates 53 are each moved radially outward, by the simple camming action of the bottoms of the cam grooves 47 120 against the rollers 52.

By virtue of this arrangement the operator, by using the treadle as above described, can cause the hat brim to be gripped, while the handle 46 of the cam ring 45 occupies a position at the left limit of its travel, as indicated in Figure 1; and then with the hat brim thus gripped the operator, by grasping the handle 46 and rocking the cam ring 45 slightly in a counter-clockwise direction, can cause the foot plates 53 all to move radially outward, thus stretching the brim.

While the brim is thus being stretched, the crown is empty; but as soon as the brim is thoroughly stretched, and with the grippers still holding its outer edge, the crown block 66a is placed by hand in the crown, and the presser foot 31 is allowed to descend by its own weight, this movement being controlled by a movement of the hand lever 17.

The downward movement of the presser foot 31 allows the descent of the crown block well into the hat crown, the precise distance being measured by the position of the collar 32 relatively to the presser foot. By thus forcing the crown block well into the crown, the top surface of the crown block is carried a little below the plane of the brim. This leaves a little margin, so that the crown block does not quite fill the crown, and this margin allows for shrinkage of the crown. Except for this provision, the subsequent shrinkage of the crown would leave the crown a trifle too shallow for the depth of the crown block.

In Figures 10 to 14 inclusive, I show a slightly different form of mechanism for stretching the hat brim.

For this purpose I use a number of foot plates 70, somewhat like the foot plates 53, both in structure and action, these foot plates being slidably fitted between stationary slides 71, which are arranged in pairs and held rigidly in position by bolts 72.

Each foot plate 70 is provided with a pair of bearings 73, in which is journaled a shaft 74, carrying a gripping lever 75. This gripping lever has a rocking movement very much like that of any one of the rocking sectors 61.

Each gripping lever 75 is provided with a jaw 76, and mating this jaw is another jaw 77, carried by the adjacent foot plate, as may be understood from Figure 10.

Each foot plate 70 is connected with a pair of springs 78, which are secured to the adjacent stationary slide rails 71. The tendency of the springs is to force the foot plates radially inward, after the manner above described for the foot plates 54.

The gripping levers are at their outer ends pivotally connected with tension rods 79, the latter being connected at their lower ends to bolts 80, as indicated in Figure 10, these bolts being carried by a spider 81, as shown in Figure 12.

A tensile spring 82 is connected with the middle of the spider 81, and extends upwardly therefrom. A turnbuckle 83 is connected with the top of the spring 82, and with a fixture 84, carried by the framework. The spider 81 is connected with the treadle 67. That is, the plate 85 is substituted for the plate 69, shown in Figure 8.

The operator, by depressing and releasing the treadle 67, causes the gripping levers 75 to be rocked back and forth, and thus to grip and release the hat brim 66.

In Figure 14 I show a mechanism somewhat similar to the one appearing in the upper portion of Figure 4, and used for forcing the block 66a into the crown of the hat, to a distance adequate to allow for shrinkage of the hat body.

A presser foot 86 carries a pair of clamping screws 87. These extend out through slots 90 in a plunger ring 88. The lifting ring is carried by extension bars 89, similar to the extension bars 21 above described.

The presser foot 86 is adjustable relatively to the lifting ring 88.

The operator by loosening the screws 87 can raise or lower the presser foot 86 and by then tightening the screws can clamp the presser foot in its new position. Thus by adjusting the presser foot it can be made to protrude a little below the adjacent lower edge of the plunger ring 88.

The purpose in having the presser foot 86 adjustable relatively to the plunger ring 88 is to enable the pressed foot to extend a little into the hat crown, as shown in Figure 14, and thus to force the crown block well down into the crown of the hat, so as to allow for shrinkage of the crown.

During the operation of the machine, the operator from time to time allows the escape of exhaust steam from the steam chamber, which he does by opening the gate valve 39 by means of the handle 40.

In either of the two forms of my invention the hat forming ring is provided with an elliptical portion 48 which is removable, replaceable, and interchangeable. The purpose of the elliptical portion 48 is to adapt the hat forming ring for hats of different sizes. For this purpose, the elliptical member 48 is simply lifted out of position and replaced by another elliptical member of the same kind, but having an aperture of a different cross diameter, and thus adapted for a hat of a different size. The elliptical member 48 is provided with dowels 48a, which fit into grooves carried by the other portion 49 of the hat forming ring, as may be understood from Figures 16 and 17.

In either of the two forms of my invention, the operator pursues essentially the same steps. Speaking broadly and in a general practical way, he uses the hand lever 17 to raise and lower the presser foot; he uses

the treadle to grip and release the outer or peripheral portion of the hat brim; he uses the handle 46 to stretch the hat brim; he employs the hand valve 37 to turn steam into the steam chamber; and he operates the handle 40 to discharge the exhaust steam from the steam chamber.

The operation of my device may be readily understood from the foregoing description.

10 Assume that the form of my machine shown in Figure 1 is in the condition indicated for it in that figure. Here the machine contains a hat body which has just been finished.

The operator grasps the hand lever 17 and 15 raises it, thus lifting the presser foot 31 out of engagement with the crown block 66a. Next he depresses the treadle 67 and holds it down, thereby causing the sectors 61 to be rocked into the positions indicated for them 20 in Figure 4. This releases the hat body, which the operator now removes by hand, along with the crown block. Next he places in the machine another hat body, its crown being empty, and by releasing pressure of his foot 25 upon the treadle, allows the same to rise. Thus the sectors 61 are allowed to rock back into their respective normal positions, and they grip the outer or peripheral edge of the hat brim, as may be understood from Figure 30 1.

The operator next opens the hand valve 37 and admits live steam into the steam chamber 36. The steam in entering spreads underneath the baffle plate 36a, and diffuses upwardly around the edges thereof, as may be understood from the form of the baffle plate as indicated in Figure 3. The steam in entering the steam chamber is distributed more or less equally, so that its effect upon the 40 hat body is as near as practicable uniform.

Next the operator grasps the handle 46, and by rocking the cam ring 45 as above described, causes the foot plates 53 to be forced radially outward, thereby stretching the hat 45 brim 66.

Then the operator opens the gate valve 39 by means of the handle 40, and thus allows the exhaust steam to escape from the steam chamber through the blower, as indicated by the 50 legend at the right of Figure 1. Because the steam is exhausted at a point removed a little distance from the hat body, the steam in escaping does not cause the hat body to be heated or moistened unequally, or to be misshapen.

This leaves the apparatus in the condition indicated for it in Figure 1, as at the start.

The action of the mechanism shown in Figures 10 to 12 inclusive is essentially the same as that just described with reference to other figures, due allowance being made for slight differences in forms of various parts as above described.

I find that hat brims, stretched as above 65 described upon either form of my mecha-

nisms, are not only stretched uniformly, but are given a marked tendency to retain afterward the forms into which they are thus brought.

I do not limit myself to the precise mechanism shown, as variations may be made therein without departing from my invention, the scope of which is commensurate with my claims.

Having thus described my invention, what 75 I claim as new and desire to secure by Letters Patent is as follows:—

1. In a machine for treating hat bodies, the combination of a steam chamber, a hat forming member fixed relatively thereto and provided with means for supporting a hat body extending partially thereinto, a plurality of foot plates slidably mounted in position and adapted to be moved outwardly in order to stretch the hat brim, gripping jaws carried by said foot plates for gripping the outer edge of said hat brim, a plurality of rollers carried by said foot plates, and a cam ring connected with said steam chamber and engaging said rollers, said cam ring being controllable by the operator for shifting the positions of said rollers and thereby causing said foot plates to be moved outwardly.

2. In a hat forming machine the combination, with a frame and a steam chamber connected therewith, of a hat forming ring carried by said frame for supporting a hat body extending into said steam chamber, a plurality of gripping mechanisms carried by said frame for grasping the brim of said hat body, and means for causing said gripping mechanisms to move, to unequal distances relatively to said hat forming ring, in order to stretch different portions of said brim unequally.

3. In a hat forming machine the combination, with frame and a hat forming ring carried thereby, of a plurality of gripping mechanisms disposed about said hat forming ring so as to grasp different portions of said hat brim, and mechanism connected with all of said gripping mechanisms for moving them to unequal distances relatively to said hat forming ring, in order to stretch some portions of said hat brim more than other portions thereof.

4. In a machine for treating hat bodies the combination of a steam chamber, a hat forming member provided with means for supporting a hat body extending partially into said steam chamber, a plurality of foot plates slidably mounted in position and adapted to be moved outwardly in order to stretch the hat brim, gripping plates carried by said foot plates for gripping the outer edge of said hat brim, a plurality of rollers carried by said foot plates, and cam mechanism engaging said rollers and controllable by the operator for shifting the positions of

said rollers in order to cause said foot plates to move outwardly.

5. In a machine for treating hat bodies the combination of a steam chamber, a hat forming member fixed relatively to said steam chamber and provided with means for supporting a hat body extending partially therewith, a plurality of foot plates slidably mounted in position and adapted to be moved 10 outwardly in order to stretch the hat brim, gripping jaws carried by said foot plates for gripping the outer edge of said hat brim, a plurality of extending members carried by said foot plates, and a cam ring connected 15 with said steam chamber and encircling the same, said cam ring engaging said extending members and being controllable by the operator for shifting the positions of said extending members and thereby moving said foot 20 plates outwardly.

Signed at New York city, in the county of New York and State of New York, this 9th day of January, 1928.

GEORGE W. CUMING.
